(57) **CLAIM**

The ornamental design for a adjustable data processing device, as shown and described.

DESCRIPTION

FIG. 1 is a front perspective view of the data processing device with a display in a first position and with a front bumper attached;

FIG. 2 is a front perspective view of the data processing device with a display in a first position and with the front bumper detached;

FIG. 3 is a front perspective view of the data processing device with a display in a second position and with the front bumper attached;

FIG. 4 is a front perspective view of the data processing device with a display in a second position and with the front bumper detached;

FIG. 5 is a back perspective view of the data processing device with a display in a first position and with a back bumper attached;

FIG. 6 is a back perspective view of the data processing device with a display in a first position and with the back bumper detached;

FIG. 7 is a top perspective view of the data processing device with a display in the second position and with the front bumper attached;

FIG. 8 is a top perspective view of the data processing device with a display in the second position and with the front bumper detached; and,

FIG. 9 is a top perspective view of the data processing device with a display in the first position and with the front bumper attached.
